MARK D. MITCHELL, OF INDEPENDENCE, KANSAS

TORPEDO FOR SHOOTING OIL WELLS

Application filed July 29, 1922. Serial No. 578,387.

It is a common practice in the operation of oil wells to explode a charge of nitroglycerine or other high explosive in a well at the level of the oil bearing rock for the purpose of 5 giving better access of the oil to the pocket in the well. For this purpose the charge of nitroglycerine is lowered to the proper position and detonated electrically by means which need not be described herein. This 10 requires the use of wires extending from the battery above ground to the detonator which frequently become broken or short circuited. Thus in many cases during the drilling of the well the wall of the hole caves in generally 15 well down toward the bottom of the hole. When this happens it is necessary to shut off the cave by means of a string of casing covering the caved or loose portion. When the casing is pulled, rocks, etc. is apt to 20 fall upon the shot. As the wires connected to the shot run through the casing the latter must be pulled out over the wires and this results in a considerable loss of time due to handling the wires, the insulation on the 25 wires is frequently broken and a short circuit thereby created or the cave falls in on the wires and breaks them, requiring an expensive replacement. My invention dispenses with the use of an electrically operated detonator and hence with the complications and 30 difficulties resulting from the use of the wires to which reference has been made above.

My invention comprises a timed detonator which may be set to explode at any desired 35 period after the setting and which is entirely self-contained so that it may be lowered on top of the main charge of explosive to detonate the latter. Being entirely self-contained it is not affected by the withdrawal of the casing or by the fall of material from the wall of the hole. My improved device comprises a shell or container enclosing a relatively small charge of high explosive, a detonator and a clock-controlled 40 hammer or firing pin for exploding the detonating charge. It is necessary that the container and its contents be heavier than water and that the container be water-tight and 45 capable of resisting great pressure of water

which may occupy the hole for some distance above it.

In the accompanying drawings, Fig. 1 is a side elevation partly in section of a detonator or shot embodying my invention; Fig. 2 a 55 transverse horizontal section of the same; Fig. 3 a plan of a detail; and Fig. 4 a vertical section of an oil well showing the detonator and main charges of explosive in place, the former being not yet released from 60 the lowering wire or cable.

In the specific form of the invention chosen for exemplification, the container 4 is shown as of malleable iron, generally cylindrical and with a rounded lower end. It is divided 65 into an upper and a lower compartment, the upper compartment receiving a clock mechanism 10 and the lower compartment 6 being filled with high explosive such as nitroglycerine. The diaphragm or partition 5 dividing the chambers includes a horizontal portion 5^a and a vertical portion 5^b, the former constituting a support for the clock work and the latter forming a vertical extension 8 of the lower chamber 6. It is to be understood that in use, the chamber 6 and the vertical extension thereof are filled with the explosive. A detonator 9 is mounted in the vertical portion of the diaphragm. 75

The clock work 10 may be of any familiar 80 or suitable type, the ordinary round clock being shown in the drawings. The usual spindle 11 on which the hour hand of the clock is commonly mounted, extends as usual through the back of the clock casing and is provided 85 with a knurled finger wheel 12 by which it may be rotated. Beneath the finger wheel and also secured to the spindle is a snail cam 13 and the back of the clock casing is inscribed with numerals properly spaced apart 90 in a circle concentric with said spindle and preferably corresponding to units of time. Thus in Figs. 2 and 3 I have shown 24 numerals and division marks, the spaces between the latter corresponding to half hours. Obviously, the spindle might be made to rotate at half the speed when these marks and the numerals identified therewith would correspond to hours. 95

The snail cam 13 controls the firing bolt 100

14 and the latter is mounted in guides 15—16, the first named of which is mounted on the back of the clock and the latter in the form of a thimble secured to the inner face of the 5 wall of the casing. Within the thimble the bolt is provided with a head 17 and a spring 18 of considerable power, is compressed between said head and the wall of the casing so that when released the bolt is driven by 10 the spring into contact with the detonator 9. A roller 20 is journaled on a stud, 19 on the bolt and arranged to bear upon the snail cam 13. As the snail cam revolves the bolt is slowly withdrawn or set by means of the 15 engagement of the edge of the cam with the roller 20 and ultimately the roller drops off of the high point of the cam thus permitting the bolt to be driven against the detonator. In practice, the cam is set by means 20 of the time inscriptions so that the bolt is released at the desired interval after the cam is set.

The upper end of the casing or shell is 25 closed by a screw cover plate 21 which has a water tight joint with the shell. The plate is provided with perforated lugs 22 which receive the ends of a bail 23 by which the detonating device is handled. At 24 I have 30 shown a hook on the tackle for lowering the device into place.

As heretofore stated, the shell and its 35 contents are heavier than water so as to sink in any water contained in the well and when the cover is in place the device is water tight so that no water may enter and interfere 40 with the action of the clock work.

In Fig. 4 representing diagrammatically 45 and partially broken away a section of the earth through an oil well the oil bearing stratum is represented at *a* and the superincumbent strata at *b* and *c*. The well casing is shown at *d* extending as usual from the 50 surface of the earth through the superincumbent strata to the oil sand. Charges of high explosive *e* are shown at the bottom of the well and the detonator at *f*, the bail of 55 the latter being shown as not yet disconnected from the lowering cable *g*.

In shooting the well with my improved 60 detonator the main explosive charges are first lowered into the well into the position illustrated and the detonator after having received its charge of explosive, percussion cap and clock work, the latter set for operation 65 within the desired period, is closed by the cover 21 and lowered into position after which the wire may be disconnected from the bail. After the predetermined interval the 70 clock work releases the bolt 14 which strikes the percussion cap setting off the detonator charge, the explosive of which explodes the main charge with the usual effect upon the oil sand immediately surrounding the well.

I claim:

65 In a device of the class described, a water-

70 proof shell capable of withstanding relatively high pressure, a diaphragm in the shell comprising a horizontal and a vertical portion and dividing the shell into a clock chamber and an explosive chamber, a detonator mounted in the vertical portion of the diaphragm, a clock mounted on the horizontal portion of the diaphragm, a reciprocal firing bolt above the clock and in line with the detonator, a spring for forcing the 75 bolt toward the detonator and a cam operated by the clock and engaging the bolt for retracting and releasing the latter.
